(57) **CLAIM**

I claim the ornamental design for fishing chair, as shown and described.

DESCRIPTION

FIG. 1 is left side elevational view of the fishing chair (the right side view being a mirror image of the left side view) shown without an anchor extension for ease of illustration.

FIG. 2 is a front elevational view of the fishing chair shown in FIG. 1.

FIG. 3 is a rear elevational view of the fishing chair shown in FIG. 1.

FIG. 4 is a top view of the fishing chair shown in FIG. 1.

FIG. 5 is a bottom view of the fishing chair shown in FIG. 1.

FIG. 6 is a perspective view of the fishing chair shown in FIG. 1.

FIG. 7 is left side elevational view of the fishing chair with an anchor extension (the right side view being a mirror image of the left side view).

FIG. 8 is a front elevational view of the fishing chair shown in FIG. 7.

FIG. 9 is a rear elevational view of the fishing chair shown in FIG. 7.

FIG. 10 is a top view of the fishing chair shown in FIG. 7.

FIG. 11 is a bottom view of the fishing chair shown in FIG. 7; and,

FIG. 12 is a perspective view of the fishing chair shown in FIG. 7.
